To all whom it may concern:

Be it known that I, Leonard H. Volk, of the City of Chicago, in the County of Cook, and State of Illinois, have invented or produced a new and original Design in round relief of a Statuette of Senator Stephen A. Douglas, and I do hereby declare that the following is a full and exact description of the same,

Height of Statuette, above mentioned, two feet, and now cast in plaster of paris. Stands in an erect posture in the act of speech, with the right hand extended, and the left hand placed across the breast holding a scroll. Head bare, the right foot advanced beyond the left one. Dressed in frock coat buttoned up with buttons and borts.

What I claim as my invention, and desire to secure by letters patent, is the design for a Statuette as above described and represented in the accompanying drawings.

Attest,

Lev. S. A. Douglas. 3
